UNITED STATES PATENT OFFICE

WILLIAM H. RIFE, OF CHICAGO, ILLINOIS

DUPLEX ENVELOPE

Application filed September 13, 1928. Serial No. 305,669.

This invention relates to envelopes and more particularly to duplex or combination envelopes, having for its object an improved duplex envelope of a design and construction effecting a considerable saving of paper, while affording a convenient and substantial container for mail matter.

Other objects and advantages of the method and construction herein employed will appear more fully in the hereinafter specification, when taken in connection with the accompanying drawings, in which:

Fig. 1 is a front view of an envelope embodying my invention.

Fig. 2 is a transverse section taken on line 2—2 of Fig. 1.

Fig. 3 is a view of the reverse side of the envelope, and

Fig. 4 is a transverse section taken on line 4—4 of Fig. 3.

In the drawings, 8 designates the body portion of envelope A, having top and bottom flaps 9 and 10 respectively, which are folded and gummed to form a sealed back 11. A flap 12 permanently closes the envelope A at one end, while the sealing flap 13 may be used to entirely close the envelope against inspection of contents; or it may be tucked into the main compartment 14 in the usual manner for enclosure of other than first class matter.

As an important feature of my invention, the blank 15 having side flaps 16, 17 and a bottom flap 18, all sealed to the front portion 8 of the envelope A, is provided. The top flap 19 of the blank 15 is gummed about the border, as best shown in Fig. 1, while on the back of the strip 19' which lies immediately above the longitudinal slot 20, a gummed surface 21 is also provided. The blank 15 as applied to the envelope A constitutes a second envelope or container either for first class mail, or, if the flap 19 is merely tucked into the slot 20 leading to the inner compartment 22 of the smaller envelope, for mail of other classification.

When the smaller envelope is to be used for first class mail, the gummed surface 21 will be sealed against the front of the large envelope A and the top flap 19 then folded

over and sealed to the top surface of the smaller envelope or container.

Particular attention is called to the fact that by the present construction and method I am enabled to take a finished envelope of the A type indicated, having a large compartment and then to form therewith a smaller compartment for enclosing first class sealed matter or circulars, as desired, in the manner indicated, by merely pasting, gumming, or otherwise affixing by machine process the blank 15 to the larger container A. It will be observed that in the formation of the smaller container the front wall of the large envelope A serves also as the back wall of the smaller container, in this manner a substantial saving of paper stock being secured. Blank 15 is practically an envelope with the front wall removed, the flap 19 being the conventional sealing flap.

It is to be understood that slight changes may be made in form, proportion and arrangement of parts; hence I do not confine myself to the details as set forth but desire to avail myself of such variations and embodiments as fairly fall within the scope of the appended claims.

What I claim as new and desire to secure by Letters Patent is:

1. A duplex envelope comprising in combination an individual complete envelope having a separate comparatively large compartment for the reception of mail matter, a second envelope directly gummed to said individual envelope after the front wall of the second envelope has been removed and the bottom and end flaps have been unfolded and sealed to the exterior surface of the front wall of the individual envelope, said second envelope being also provided with a flap adapted to be sealed over a slot formed at its upper part of the second envelope, said slot serving optionally to admit mail matter of different classifications, whereby the second envelope may be used to enclose first class mail matter and to enclose mail matter of other description, while said individual envelope may enclose other than first class matter.

2. A duplex envelope comprising, in com-

bination, an individual complete envelope having a separate comparatively large compartment for the reception of mail matter, a blank provided with side and bottom flaps
5 gummed directly to said individual envelope and also provided with a sealing flap whereby a second envelope is formed between said blank and said individual envelope, said blank provided with a slot adjacent said
10 sealing flap whereby said second envelope may be used to enclose mail matter of different classifications.

In testimony whereof I have signed my name to this specification.
